(57) **CLAIM**

The ornamental design for a hay feeder, as shown and described.

DESCRIPTION

FIG. 1 is a front top perspective view of the hay feeder of the present invention;

FIG. 2 is a rear bottom perspective view of the hay feeder shown in FIG. 1;

FIG. 3 is a front elevational view of the hay feeder shown in FIG. 1;

FIG. 4 is a rear elevational view of the hay feeder shown in FIG. 1;

FIG. 5 is a left side elevational view of the hay feeder shown in FIG. 1;

FIG. 6 is a right side elevational view of the hay feeder shown in FIG. 1;

FIG. 7 is a top plan view of the hay feeder shown in FIG. 1; and,

FIG. 8 is a bottom view of the hay feeder shown in FIG. 1. Any surface marks in the drawings are merely shading lines used to convey the contours of the hay feeder, and not surface ornamentation.

The broken line showing of a slow feed hay net and hay in FIG. 1, illustratively depicts exemplary in-use elements that form no part of the design claim but are included to show the invention in context.
